US00D839886S

(12) **United States Design Patent** (10) Patent No.: **US D839,886 S**
 Yamazaki et al. (45) Date of Patent: ** Feb. 5, 2019

(54) **DISPLAY SCREEN WITH GRAPHICAL USER INTERFACE**

(71) Applicant: **Mitsubishi Electric Corporation**,
 Tokyo (JP)

(72) Inventors: **Satoshi Yamazaki**, Tokyo (JP); **Ayako Nagata**, Tokyo (JP)

(73) Assignee: **Mitsubishi Electric Corporation**,
 Tokyo (JP)

(**) Term: **15 Years**

(21) Appl. No.: **29/619,764**

(22) Filed: **Oct. 2, 2017**

(30) **Foreign Application Priority Data**

Apr. 19, 2017 (JP) 2017-008411
 (51) LOC (11) Cl. **14-04**
 (52) U.S. Cl. ..... **USPC D14/485**

(57) **CLAIM**

The ornamental design for a display screen with graphical user interface, as shown and described.

DESCRIPTION

The FIGURE is a front view of a display screen with graphical user interface showing our new design.

The broken lines in the drawings illustrate portions of the display screen with graphical user interface that form no part of the claimed design.

1 Claim, 1 Drawing Sheet
